(57) CLAIM

The ornamental design for a bag for a beverage bottle, as shown and described.

DESCRIPTION

FIG. 1 is a first side view of the bag for a beverage bottle in accordance with my invention;

FIG. 2 is second side view thereof, taken from the opposite side of FIG. 1;

FIG. 3 is a first end view thereof, taken from the right side of FIG. 1;

FIG. 4 is a second side view thereof, taken from the left side of FIG. 1;

FIG. 5 is a top view thereof; and,

FIG. 6 is a bottom view thereof.

Throughout the drawings the broken lines illustrate unclaimed subject matter only and form no part of the claimed design.

1 Claim, 6 Drawing Sheets
